(74) **Attorney, Agent, or Firm:** Klauber & Jackson LLC(57) **CLAIM**

The ornamental design for a tyre, as shown and described.

DESCRIPTION

FIG. 1 is a front, left side perspective view of a tyre showing our new design;

FIG. 2 is a front elevation view thereof;

FIG. 3 is a side view thereof; and,

FIG. 4 is a partial front elevation view taken from FIG. 2 and shown in an enlarged scale.

The four (4) metal studs appearing in FIGS. 2 and 4 form no part of the claimed design.
